(57) **CLAIM**

The ornamental design for heat pipe of radiator of computer, shown and described.

DESCRIPTION

FIG. 1 is a perspective view showing the heat pipe of radiator of computer of my new design;

FIG. 2 is a front elevation view thereof;

FIG. 3 is a rear view thereof;

FIG. 4 is a left side elevation view thereof;

FIG. 5 is a right side elevation view thereof;

FIG. 6 is a top plan view thereof;

FIG. 7 is a bottom plan view thereof; and,

FIG. 8 is a perspective view thereof shown exploded for ease of illustration.
